UNITED STATES PATENT OFFICE.

ARNOLD J. ZAPP, OF AMSTERDAM, NEW YORK, ASSIGNOR TO STEPHEN SANFORD & SONS, INC., OF AMSTERDAM, NEW YORK, A CORPORATION OF NEW YORK.

DESIGN FOR A RUG.

Application filed January 3, 1929. Serial No. 29,485. Term of patent 7 years.

To all whom it may concern:

Be it known that I, ARNOLD J. ZAPP, a citizen of the United States, residing at the city of Amsterdam, county of Montgomery, and State of New York, have invented a new, original, and ornamental Design for a Rug, of which the following is a specification, reference being had to the accompanying drawing, forming part thereof.

The drawing is a face view of one-fourth of a rug, the remaining three-fourths being a repetition of the detailed corner illustrated.

I claim:

The ornamental design for a rug, substantially as shown and described.

ARNOLD J. ZAPP.
